TETHER BALL TOY

George L. Urquhart, 1267 Creston Place, North
Kamloops, British Columbia, Canada

Filed June 8, 1971, Ser. No. 151,163

Term of patent 7 years

Int. Cl. D21—01

U.S. Cl. D34—15

FIG.1.

FIG.2.

FIG. 1 is a side perspective view of the tether ball toy, embodying the features of my new design, and FIG. 2 is an end elevation view thereof.

I claim:

The ornamental design for a tether ball toy, substantially as shown and described.
